UNITED STATES PATENT OFFICE.

JOSEPH RAU AND WINCE RAU, OF FAYETTE, IOWA.

STOCK-FEEDER.

1,151,901.

Specification of Letters Patent. Patented Aug. 31, 1915.

Application filed November 6, 1912, Serial No. 729,917. Renewed January 27, 1915. Serial No. 4,753.

To all whom it may concern:

Be it known that we, JOSEPH RAU and WINCE RAU, citizens of the United States, residing at Fayette, in the county of Fayette and State of Iowa, have invented certain new and useful Improvements in Stock-Feeders, of which the following is a specification.

This invention relates to improvements in stock feeders, more particularly to devices of this character employed for feeding calves and like young animals, and has for one of its objects to improve the construction and increase the efficiency and utility of devices of this character.

Another object of the invention is to provide a simply constructed device divided into a plurality of independent feeding compartments and a supply compartment, and wherein provision is made for supplying each of the feeding compartments with an equal amount of the feed.

Another object of the invention is to provide a simply constructed device divided into a plurality of feeding compartments and a supply compartment and a plurality of controlling valves between the compartments, and means for automatically actuating the controlling valves to permit the feed to pass from the supply compartment into the feeding compartments.

With these and other objects in view, the invention consists in certain novel features of construction as hereinafter shown and described and then specifically pointed out in the claims, and in the drawings illustrating the preferred embodiment of the invention.

Figure 1 is a plan view of the improved device with the hinged closure in position; Fig. 2 is a plan view without the hinged closure; Fig. 3 is a longitudinal section on the line 3—3 of Fig. 1; Fig. 4 is a transverse section on the line 4—4 of Fig. 1.

Corresponding and like parts are referred to in the following description and indicated in all of the views of the drawings by the same reference characters.

The improved device may be constructed of any suitable material and of any required size and divided into any required number of feeding compartments, and also with a supply compartment of any required size,

but for the purpose of illustration, the device is shown having four of the feeding compartments.

The improved device comprises a trough-like structure 10 closed at the ends, as shown at 11—12, and provided with a plurality of transverse partitions 13, with one of the partitions spaced a considerable distance from the end 12, whereby a relatively large compartment 14 is produced, together with a plurality of small compartments 15. The larger compartment 14 is designed to contain the supply of feed, while the smaller compartments are designed to contain the supplies for the individual animals. The trough-like structure 10 is provided with a closure 16 hinged at 17 to a supporting strip 18, the latter being attached permanently to the trough. The closure 16 is shorter than the trough, whereby an opening 19 is formed through which the feed is supplied to the compartment 14.

Each of the partitions 13 is provided with an opening 20 at its lower side to permit the feed to pass from the compartment 14 to each of the smaller compartments 15. Hinged at 21 to each of the partitions 13 is a controlling valve 22, each valve being preferably provided with a spring 23 to hold it yieldably closed over the adjacent opening 20.

Mounted for rotation through the casing 10 at the upper portion of each of the smaller compartments 15 is a rock-shaft 24 having a crank 25 at one end externally of the casing and with an arm 25' depending from the shaft internally of the casing and 90 engaging at its free end in a link 26 connected respectively to the valves 22. The cranks 25 are coupled together by an operating bar 27 so that the shafts may be actuated simultaneously by motion applied to the bar 27. 95 Pivoted at 28 to the casing 10 is an operating lever 29, and connected between the lever 29 and the bar 27 is a rod 30. By this means it will be obvious that the valves 22 may be simultaneously actuated by simply manipulating the lever 29. Preferably an inclined longitudinally extending bottom 31 will be located within the feed supply compartment 14 and provided with a depending terminal 32, so that all of the feed will pass into the 105 smaller compartments 15, and so that none

of it will be retained in the larger compartment 14. Suitable supporting feet 33 are arranged beneath the trough, as shown.

It will thus be obvious that a simply constructed device is produced, which may be inexpensively manufactured and of any required size or capacity.

Having thus described our invention, what we claim and desire to secure by Letters Patent is:—

1. In a stock feeder, a trough divided by partitions into a supply receptacle and a plurality of feeding receptacles and having openings providing communication between the feed receptacles and an opening between the supply receptacle and the adjacent feed receptacle, a controlling valve for each of said openings, and means for simultaneously actuating said valves.
2. In a stock feeder, a supply receptacle, a plurality of feeding receptacles, said feeding receptacles having communicating openings and said supply receptacle having an opening communicating with one of the feeding receptacles, a controlling valve for each of said openings, and means for simultaneously actuating said valves.
3. In a stock feeder, a trough divided by partitions into a supply receptacle and a plu-

rality of feeding receptacles and having 30 openings providing communication between the feed receptacles and an opening between the supply receptacle and the adjacent feed receptacles, a controlling valve for each of said openings, a separate shaft extending 35 through each of said feeding receptacles and each provided with a crank arm, an arm extending from each of said shafts and engaging said valves, a bar connected to said crank arms, and means for actuating said bar to 40 simultaneously actuate said shafts and cause the simultaneous operation of the valves.

4. In a stock feeder, a trough divided by partitions into a supply receptacle and a plurality of feeding receptacles, each of said partitions having an opening, a closure for said feeding receptacles and extending partly over the supply receptacle, a controlling valve for each of said openings, and means for simultaneously actuating said 50 valves.

In testimony whereof we affix our signatures in presence of two witnesses.

JOSEPH RAU. [L. S.]
WINCE RAU. [L. S.]
